PUMP

Dennis L. Eidson, Barrington, Ill., assignor to Hills-McCanna Company, Chicago, Ill., a corporation of Illinois

Filed Feb. 18, 1960, Ser. No. 59,440

Term of patent 14 years

(Cl. D65—1)

FIG. 1.

FIG. 2.

FIG. 1 of the drawing is a front perspective view of a pump embodying my new design; and

FIG. 2 is a fragmentary rear perspective view of the pump portion extending forwardly and outwardly to the left as seen in FIG. 1.

The characteristic features of my design for the pump disclosed reside in the unit that extends forwardly and outwardly from the left end as seen in FIG. 1, and as shown in FIG. 2.

The motor, reducer and driving mechanism on the inside are shown in broken lines as being conventional.

The rear and the side not shown are substantially plain and unornamented.

I claim:

The ornamental design for a pump, substantially as shown, and described.
